UNITED STATES PATENT OFFICE.

ALEXANDER E. SORUM, OF PORTLAND, OREGON, ASSIGNOR, BY MESNE ASSIGNMENTS, TO REMINGTON ARMS COMPANY, INC., OF NEW YORK, N. Y., A CORPORATION OF DELAWARE.

REGISTER-RESETTING MECHANISM.

Original application filed August 3, 1914, Serial No. 854,837. Divided and this application filed October 28, 1916. Serial No. 128,258.

To all whom it may concern:

Be it known that I, ALEXANDER E. SORUM, a citizen of the United States, residing at Portland, in the county of Multnomah and State of Oregon, have invented certain new and useful Improvements in Register-Resetting Mechanism, of which the following is a specification.

This invention has relation particularly to registering machines of the type utilizing a plurality of counting or indicating wheels or devices susceptible of actuation to register, indicate or record amounts of accounting transactions.

The invention involves essentially certain novel zeroizing or normalizing mechanism for accounting means of the type above referred to, and the improvements hereinafter set forth comprise a division of my application for patent, Serial Number 854,837, filed August 3, 1914.

An especial object of the improvements of this invention has been to devise simple means to control the zeroizing action of counting wheels or equivalent devices, which means is adapted for use equally as well in cooperation with the wheels or corresponding parts of a single counting device, or in conjunction with the registering or accounting instrumentalities of a plurality of counting devices susceptible of being actuated for normalizing purposes by some simple means common to all of said devices.

A full understanding of the invention will be had upon reference to the accompanying drawings in which:

Figure 1 is a top plan view, with parts broken away, showing more particularly two denominational counters or registers comprising suitable registering wheels, together with the resetting controlling means of the invention, certain of the wheels being illustrated in section.

Figure 2 is a front elevation of a counting or registering mechanism adapted to form an attachment for some other machine having suitable actuators for the counting devices, a plurality of which are mounted upon

a common shaft, the casing intended to enclose the counting devices being omitted, and only several of said devices being illustrated in detail.

Figure 3 is a fragmentary bottom plan view of certain of the parts shown in Figures 1 and 2.

Figure 4 is a sectional view of the same on the line 4—4 of Figure 2 and showing clearly the locking member for the resetting shaft.

Figure 5 is a sectional view taken about 60 on the line 9—9 of Figure 2.

Figure 6 is a view similar to Figure 5 taken on the line 10—10 of Figure 2, certain supporting means for the counting mechanism as a whole being illustrated as well as 65 a conventional form of actuator for one of the counting devices.

Figure 7 is an enlarged detail view bringing out more clearly the locking means for the resetting shaft.

Figure 8 is a combined view showing details of the transfer mechanism for the wheels of each counting device, the transfer mechanism being illustrated as when in process of carry-over and also in its normal position.

Figure 9 is a detail view of one of the friction springs carried by the counter shaft.

Figure 10 is a perspective view showing more clearly certain parts of the registering 80 and zeroizing mechanism.

The invention is illustrated in the drawings in connection with a counting apparatus comprising a base or supporting plate 201 adapted to be mounted upon a registering or similar machine having actuators 3, one for each of the counting devices, a plurality of which are mounted upon said base 201. It is to be understood, however, that the zeroizing mechanism to be hereinafter 90 set forth in detail need not necessarily be employed in connection with the particular form of counting device or devices.

Referring especially to Figures 2 and 6, it will be observed that the plate 201 has 95 inwardly projecting hooks 202 at the lower

portion of its opposite ends adapted to engage over supporting rod 203. In like manner other hooks 204 at the opposite upper ends of the plate 201 engage the movable 5 arms 205 on a shaft 206, and the arms 205 are adapted to be moved so as to connect the plate 201 and the counting devices thereon with the machine which comprises the actuators 3, one of which will operate each 10 counting device. Furthermore, each counting device, as seen in the drawings, comprises a plurality of counting wheels 213.

The means by which the actuators 3 are operated being immaterial to the invention, 15 no further description thereof will be given.

The plate 201 is provided with a plurality of openings at its lower portion through each of which one of the counter actuators 3 is adapted to operate, the front end of the 20 actuator being engageable with a lug 207 on a slide 208. The counting devices for each of the actuators 3 are substantially alike and therefore only one will be described in detail, the same including the slide 208 25 previously mentioned having its lug 207 and said slide being supported by a bracket 209 fastened to the plate 201. The slide 208 has a vertical lug 208' provided with a lateral pin 208'' which enters the bifurcation 30 of an extension 210 of a disk 211 mounted on the resetting shaft 212. At one side of the disk 211 are the several counting wheels 213 which may be styled the usual units, tens, hundreds and thousands 35 wheels, the number of these wheels being adapted to be increased according to the requirements. The disk 211 carries at one side thereof the pawls 214 pressed outwardly by spring means as at 215, said pawls en- 40 gaging with teeth 216 formed internally on the units wheel 213. It is to be understood that the disk 211 and the counting wheels are coaxially mounted loose on the resetting shaft 212 and there is provided between each count- 45 ing wheel 213 and its next adjacent counting wheel a suitable carryover mechanism such as illustrated in Figure 8. This transfer mechanism is substantially the same as that of United States Patent No. 728,502, issued 50 May 19, 1903, to W. L. Sandage and no claim is, therefore, made to the mechanism as shown therein. As seen in Figure 8, however, the units wheel 213 has pivoted thereto a transfer pawl 213' which when the 55 nose thereof engages a projection 217 and the tail thereof is received in a recess 218, interlocks the units wheel 213 with the tens wheel 213 at its side, the tens wheel having projections or teeth 216 on its inner periph- 60 ery adapted to be engaged by the pawl 213' when so adjusted. The projection 217 is in the nature of a cam, being formed on a collar 217a keyed or otherwise fixed on the resetting shaft 212. Obviously at one 65 time during each revolution of the units

wheel 213, the pawl 213' thereof, which is housed in the recessed side of the tens wheel, is caused to move outwards at its nose into engagement with the teeth 216 of the wheel 213 of higher denomination, whereupon the 70 increment of movement imparted to the units wheel or wheel of lower denomination at this time is likewise imparted to the wheel of higher denomination because the two are temporarily interlocked during one-tenth 75 portion of their revolution, in an obvious manner. When this increment of movement happening at the time of transfer is ended, the tail of the pawl 213' rides out of the recess 218 and disengages the pawl of the 80 counting wheel of lower denomination from the wheel of higher denomination in an ob- 85 vious manner. The specific mode of trans- fer or carryover above described is immaterial to this invention because it is con- templated to use any desirable type of carry- over for the counting wheels of each count- 90 ing device, the wheels of all of said devices being carried by the common shaft 212, the latter forming not only the axis for the 95 counting wheels but also a resetting means.

Every time one of the actuators 3 is op- 100 erated its outer end engages the slide 208, thereby moving the latter outwards against the tension of a spring 219. At the same 95 time the connection of the slide 208 with the disk 211 partly rotates the latter and such movement is correspondingly imparted to the units wheel of the counting device, the movement being transferred to the wheels 100 of higher denominations in the customary manner above explained.

Counter resetting mechanism.

As clearly shown by Figure 2 of the draw- 105 ings, the counting wheels of all of the count- 110 ing devices carried by the plate 201 are mounted upon the common resetting shaft 212. Each counting device comprises as its main parts the counting wheels 213 referred 115 to, the disk 211 for each set of wheels and the spring retracted slide 208 interlocked with said disk. Assuming that the actuators 3 have been operated through a series of transactions of the machine to which my at- 120 tachment is affixed, and it is desired to nor- 125 malize the various counting devices, the op- erator will depress the finger piece 220 of a locking lever 221 which is mounted on a locking shaft 222 and formed with a lug 223 adapted to engage in a notch 224 formed in the locking wheel 225 rigidly secured to the shaft 212. The depression of said lever 221 which is normally held by a spring 226 in locking engagement with the wheel 225, does 125 two things. First the shaft 222 is rocked with the lever as the lug 223 is disengaged from the notch 224, and the wheel 225 and the shaft 212 are released and free to rotate 130 in the brackets 227 supporting the said shaft.

on the plate 201. The shaft 222 not only carries the locking lever 221 at one end but at the other end an arm 228 is mounted, the said arm 228 and the lever 221 having inwardly extending studs or pins 229 projecting beneath a resetting control member or plate 230 (see Figures 4 and 7). The resetting control member or plate 230 extends lengthwise of the main supporting plate 201 and is formed with a flange 230' adapted to engage with resetting lugs 231 one of which is provided on the peripheral portion of each counting wheel. In other words, under normal conditions there is mounted on the shaft 222 a resetting plate having a spring 232 connected therewith and with the locking lever 221 (see Figure 4), said spring tending to move the flange 230' of the resetting control plate into engagement with the resetting or zeroizing lugs 231 of the counting wheels. However, the spring 232 connected with the lever 221 is of greater tension than the spring 233 and thus when the lever 221 interlocks with the locking wheel 225, the pins 229 carried by the lever 221 and by the arm 228, bear against the under side of the control plate and hold the latter in a position in which it cannot engage with the zeroizing lugs 231. The above action results from the fact that as the lever 221 tilts at its lower end towards the wheel 225 to engage in notch 224, the upper end tilts away from the wheel so that pin 229 on lever 221 may engage and shift the plate 230 to render its flange 230' inactive relative to the lugs 231. The arm 228 rocks with lever 221, of course, and the pin 229 of the arm acts on the plate 230 in the same manner as the pin 229 of said lever. The depression of the locking lever 221, however, moves said lever to disengage it from the locking wheel 225 and simultaneously the shaft 222 is rocked to permit of very slight downward movement of the control plate 230 and its flange 230' so that the flange 230' is in the path of rotation of the lugs 231 and when the resetting shaft 212 is turned by the knurled knob or handle 233, the various counting wheels of the several counting devices will be zeroized owing to the engagement of the lugs 231 with the flange 230' of the control plate 230. At this particular time the notch 224 will be again opposite the locking lug 223 and the latter will spring into the notch under the action of the spring 232 normalizing the locking lever 221, locking the shaft 212, and rocking the shaft 222 sufficiently to cause the pins 229 of the parts 221 and 228 to raise the control plate into a position wherein its flange 230' is out of the path of rotation of the lugs 231.

If desired, as seen in Figure 6 especially, the slide 208 may have an extra lug 7 at a little higher elevation than the lug 207. By engagement of the actuator 3 with the lug

7 double the amount of movement of the slide may be effected as compared with the movement when the actuator 3 engages the lug 207. Such engagement and resulting movement may be used to cause two increments of movement of a register, as for registering up a two penny selection, a two dime selection, etc.

Having thus described the invention, what is claimed is:

1. In a machine of the class described, the combination of a plurality of counting wheels, a resetting shaft for said wheels, actuating means for the shafts; means normally locking said shaft from rotation, a resetting control member, means on the counting wheels to cooperate with the control member for zeroizing purposes, and means other than the shaft actuating means for releasing the locking means for said shaft and thereby moving the control member into a position to positively act on the counting wheels for resetting purposes.

2. In a machine of the class described, the combination of a plurality of counting devices, a resetting shaft on which said devices are mounted, actuating means for the shaft, a resetting control plate common to all of the counting devices, means normally locking the resetting shaft against rotation and holding the resetting plate in an inoperative position relative to said counting devices, and a simple means other than the actuating means aforesaid for unlocking said shaft and moving the resetting plate into a position wherein it is adapted to cause positive stopping of the counting devices.

3. In a machine of the class described, the combination of a plurality of counting devices, a resetting shaft on which said devices are mounted, actuating means for said shaft, a pivoted resetting control plate common to all of said devices for engagement therewith, means normally locking the resetting shaft against rotation and holding the said control plate in an inactive position relative to said counting devices, and means for unlocking said shaft and simultaneously moving the control plate into cooperative relation with the counting devices including a lever, and means intermediate the lever and the control plate to permit movement of the latter to coacting engaging position in respect to the counting devices when the lever is operated to unlock the shaft.

4. In combination, a supporting and resetting shaft, a plurality of counting wheels thereon, a resetting control plate adjacent to the counting wheels, means on the counting wheels cooperative with said plate in the normalizing of said wheels, a lever adapted to lock said resetting shaft against movement, means for actuating the counting wheels, spring means normally tending to move the control plate into cooperation with

the counting wheels, a part carried by said lever and engageable with said plate to hold the plate out of cooperation with respect to the counting wheels or permit such cooperation, and spring means connected with said lever and of greater power than the spring means connected with the plate and nor-

mally acting to hold the lever in locking co-operation with the resetting shaft while maintaining the control plate out of cooperation with respect to the counting wheels. 10

In testimony whereof I affix my signature.

ALEXANDER E. SORUM.
